UNITED STATES PATENT OFFICE.

ELIHU C. WILSON AND WILLIAM W. WILSON, OF LOS ANGELES, CALIFORNIA,
ASSIGNORS TO SAID WILLIAM W. WILSON.

UNDERREAMER.

1,344,327.

Specification of Letters Patent. Patented June 22, 1920.

Application filed December 20, 1916. Serial No. 138,055.

To all whom it may concern:

Be it known that we, ELIHU C. WILSON and WILLIAM W. WILSON, both citizens of the United States, residing at Los Angeles, in 5 the county of Los Angeles and State of California, have jointly invented new and useful Improvements in Underreamers, of which the following is a specification.

This invention relates to underreamers such as are used for enlarging well holes to 10 permit the lowering of casing therein as the development of the hole proceeds. It is a particular object of the present invention to provide an improved underreamer in which 15 the cutters or expandable and collapsible cutters or members which are usually present in such a device may be capable of a relatively greater range of lateral expansion in accompaniment with a given distance 20 of play lengthwise of the underreamer body. The present underreamer constitutes an improvement upon or modification with respect to an underreamer such as that disclosed by us in a prior application for U. S. 25 Letters Patent, filed by us Sept. 27, 1916, Ser. No. 122,481, but it is to be understood that the broad aspects and features of the present invention are not confined in use and adaptation and application to any one 30 particular type and organization of underreamer, but that the same may be embodied in and applied to a wide range of varying underreamer constructions. The invention has for further objects the provision of an 35 improved underreamer which will be generally superior in point of relative simplicity and inexpensiveness of construction and organization, taken in connection with durability, freedom from liability to dis- 40 order and derangement of parts and features, facility in assemblage and dismantling or disconnecting of parts and features, positiveness and efficiency in operation, and general serviceability. A further particular ob- 45 ject of the invention consists in the formation and provision and combination of parts and features whereby the cutters or bits may be temporarily and positively retained in collapsed or contracted position to enable 50 the same to be entered within the casing

prior to lowering the underreamer to the zone of performance. Certain features of cutter formation incident to their co-operation with the other features of the construction likewise enter into the present invention. 55

With the above and other objects in view, the invention consists in the novel and useful provision, formation, construction, combination, association and inter-relation of 60 parts, members and features, all as herein-after described, shown in the drawing and finally pointed out in claims.

In the drawing:

Figure 1 is a longitudinal sectional view, 65 partly broken away, and partly in elevation, of an improved underreamer constructed and organized to embody the invention; one of the cutters or bits being omitted for clearness of illustration;

Fig. 2 is a view similar to Fig. 1 showing the cutters in contracted or collapsed positions, such cutter being shown in expanded working position in Fig. 1; the cutters being shown held temporarily collapsed for 75 introduction within the casing in Fig. 2, in accordance with the present invention;

Fig. 3 is an elevation of the spring-actuated cutter-carrying rod shown in Figs. 1 and 2, the same being in detached position 80 and being a view at right angles to the plane of vision in Figs. 1 and 2;

Fig. 4 is a side elevation of one of the cutters shown in Figs. 1 and 2 in detached position, looking toward the inner face of the 85 shank thereof;

Fig. 5 is a detail transverse sectional view taken upon the line x^5-x^5 , Fig. 1, and looking upwardly;

Fig. 6 is a bottom end or plan view of the 90 body of the underreamer with the cutters and spring-actuated cutter-carrying rod removed; and

Fig. 7 is a detail inner face view of one of the underreamer cutters shown likewise 95 in detached position.

Corresponding parts in all the figures are designated by the same reference characters.

Referring with particularity to the drawing, the underreamer shown therein as em- 100

bodying the invention comprises an elongated body A provided with an internal longitudinal bore or chamber 7, and having at its upper end one member 8^b of a taper-
5 joint, such member being known in the art as a taper threaded pin. By this joint member the underreamer is connected with the sinker bar, jars, or other features of a string of tools utilized in the reaming operation,
10 and which string is suspended at the lower end of the cable by which the underreamer and string are vertically reciprocated in the hole in the reaming operation, pursuant to which the cutters B disposed at the lower
15 end of the reamer body are caused to attack the shoulder or annular formation beneath the casing to chip, cut or break same away so that the further lowering of the casing may be permitted. The lower end of
20 the reamer body A is shown as formed into or provided with a chamber 8 or bowl mouth, the walls of which are slightly upwardly and inwardly inclined, and at the extreme lower orifice of which are provided
25 two downwardly ranging opposed extensions or lugs 9 constituting inthrust bearings for the cutters and also provided with upper spreading bearings 9^a and lower spreading bearings 9^b which coöperate with the cutters in both the expanding and collapsing actions thereof. Within the longitudinal bore or chamber 7 in the body A, is disposed a spring-actuated rod 10 which is surrounded by a coil compression spring 11
30 which bears at its upper end upon an adjusting nut 12 threaded to the upper end of such rod 10; and the lower end of such spring 11 bears upon or is seated upon means b for assembling together the body A,
35 the rod 10 and its spring 11, and the cutters B, such means likewise serving as a stop or seat for the lower end of the spring 11.

At the lower end of the rod 10 are provided separate means c and d of operative
45 connection for the respective cutters B with such spring-actuated rod 10. Likewise, the lower end of the body A preferably adjacent to the upper region of the bowl mouth or chamber 8 is provided with a lateral
50 opening or hole 13 accommodating means e for temporarily and positively retaining the spring-actuated rod in depressed position and consequently retaining the cutters B in contracted or collapsed positions, namely,
55 the positions shown in Fig. 2.

Inasmuch as the general formation of the reamer body A and of the spring-actuated rod and its spring, and of the means b for assembling together the parts and stopping
60 the lower end of the spring, are either well known in the art or described and disclosed and claimed in said prior application by us filed, or in other applications for Letters Patent previously filed by us, and inasmuch

as the present invention particularly pertains to the formation and relative arrangement and mode of operation and principle of action of the lower end of the spring-actuated rod 10 and the means c and d thereon, together with the cutters B, and the means e for temporarily retaining the cutters in contracted positions, only brief reference will be made to such well known and heretofore produced features, emphasis and particular description and statement being concentrated upon the features particularly characterizing the present invention.

As shown, the means b comprise a key 14 which may be passed endwise through a transverse slot 15 in the reamer body A and through a further transverse elongated slot 16 in the spring-actuated rod 10 beneath the spring 11, and held in position by a lug or head 16^a at one end of the key which is received within a recess 17 in the reamer body, and by a cotter pin 18 which is passed through an opening 19 in the other end of the key 14 and engages with the body A exteriorly of the same.

The lower end of the spring-actuated rod 10 is enlarged as shown, in the portion in which the slot 16 is formed, to strengthen the same, and the extreme lower portion thereof, 10^a, is flattened at its opposed sides to receive in engagement the inner faces of the shanks of the cutters, such portion being likewise laterally expanded or broadened. This broadening provides for reception of the means c and d, each of which is shown as a separate pivot pin positively seated in such portion 10^a and preferably introduced within a recess therein within which it is firmly welded. These pins, shown as cylindrical, are when seated in their respective openings in or through the portion 10^a, disposed to project oppositely from such portion 10^a, and out of registration or coincidence. Each pin is preferably thus disposed at a separate side of the longitudinal axis of the rod 10, and their axes 110 are parallel. To each of such pins is applied a separate one of the cutters B, each such cutter having a shank portion 20 having an inner flat face 20^a and provided with a transversely or laterally elongated or enlarged socket 20^b which receives the respective pin c or d, to pivotally center the respective cutter upon and pivotally suspend it from the respective pin and resultantly from the rod 10, and eccentrically with respect to the longitudinal axis of such rod. Each cutter is mounted upon the pin c or d which is disposed at the side of the longitudinal axis of the rod 10 at which the cutter in the main operates, thus generally disposing the cutter in its working zone in the main at one side of the longitudinal axis of the spring-actuated rod. Heretofore in

underreamer practice it has been uniformly customary to mount the cutters for either tilting or oscillating or rocking action upon supports or centers substantially in registration or coincidence transversely of the cutter-carrying rod or part. The present departure, whereby the cutter and its pivotal center both are disposed in the main at one side of the longitudinal axis of the cutter-carrying rod, is one distinguishing feature of the present invention. Each cutter B is provided with a laterally ranging body portion 20^c at the lower extremity of which is provided the working or cutting edge 20^d; such body being provided at its upper end with a riding shoulder 20^e for engagement with the lower extremity 8^a of the bowl mouth 8 for coöperation to transmit the upthrust of the cutter to the body of the reamer; and likewise for engagement with the lower end of the shoe or casing 21 in Fig. 1, to produce collapse of the cutters upon the beginning of the elevation of the reamer, which is accomplished by temporary relative movement of the cutters and their rod 10, and the body A. The upper portion of each body 20^c is planed off as at 20^f, at each side to produce a downwardly and inwardly inclined shoulder 20^g which coöperates with the respective lower spreading bearing 9^b upon the respective lug 9; and the cutter body is provided beneath such shoulders 20^g with lateral shoulders 20^h, the inner faces of which form bearings coöperating with the upper spreading bearings 9^a.

The upper spreading bearings 9^a are sharply upwardly and outwardly inclined; and the lower spreading bearings 9^b partly take of a less acute upward inclination.

The means e is shown in the particular form illustrated in the drawing as including a stop pin which is of proper dimension to be freely passed into the opening 13 so that its inner end may be brought within the chamber 8 and likewise within the elongated slot 16 in the spring-actuated rod 10 when the rod is in lowered position and the cutters are collapsed or contracted. Thus the action of the spring 11 is resisted and the cutters maintained in collapsed or contracted positions for entering in the casing, until such pin is withdrawn and the spring-actuated rod is freed. It is manifest that the slot 16 is only utilized to receive this stop pin for motives of convenience and to obviate the necessity of providing any other receptive opening for such pin, although such other opening or other complementary formation upon the rod may be provided as desired. The shanks 20 of the cutters are formed to complement the upwardly and inwardly inclined inner walls of the bowl mouth 8, to such an extent as to produce a proper working fit, and at the same time to permit of pivotal action of the cutters upon their centering pins c and d. These shanks likewise impart outthrust to the inner walls of the bowl mouth 8.

The method of use, mode of operation and advantages of the improved underreamer constituting the invention will be understood from the foregoing description, taken in connection with the accompanying drawing and the following statement:

The parts of the underreamer are readily assembled together by applying the cutters to the pivot pins c and d and then introducing the rod 10 with its spring 11 through the bowl mouth 8 at the lower end of the body and into the communicating bore 7 in the body. Thereupon the spring is pushed up by inserting a suitable implement through the transverse slot 15, and the key is introduced through said slot and the slot 16, with the end thereof having the opening 19 leading. The lug or head 16^a is then brought into its final recess 17, and the cutter pin 18 is passed through the opening 19 in the key. The parts are now held assembled together subject to ready disassembling or dismantling or reversal of the steps thus described, for the purpose of removing the cutters from the spring-actuated rod to permit replacement, sharpening, dressing or repair thereof, such sharpening or dressing being frequently necessary, due to the heavy service to which underreamer cutters are subjected. When removing the key 14 a suitable implement is applied to the leading end thereof. The key is driven out in the direction opposite to that in which it is inserted. With the parts assembled, the cutters may now be drawn downwardly into the position shown in Fig. 2, the bearings 20^h riding over the upper spreading bearings 9^a and the shoulders 20^g, riding down onto the lower spreading bearings 9^b. The stop pin e may now be introduced within the hole 13 and entered in the slot 16, holding the cutters down against the compression of the spring 11, whereupon the cutters may be introduced within the casing at its upper end, and the underreamer then lowered on the cable to that point at which the cutters escape beneath the shoe or lower end of the casing. After the cutters have been so introduced in the casing, the stop pin e is withdrawn from the hole 13, and the spring freed for action to cause the cutters to expand when brought to the position last stated beneath the casing, the shoulders 20^g riding upwardly over the lower spreading bearings 9^b, the bearings 20^h riding upwardly over the upper spreading bearings 9^a, causing first an abrupt expanding action of the cutters followed by a finally more modified expanding

action, until the riding shoulder 20^a is brought into engagement with the upthrust shoulder 8^a at the lower end of the reamer body mouth. Inasmuch as each cutter is 5 pivotally mounted in the main at that side of the longitudinal axis of the reamer body in which its path of expansion lies, the expanding action is all utilized for the outward projection of the body 20^a of the cutter, to produce a full and accentuated expansion, which coincides with a minimum upward ride of the cutter over the spreading bearings. Extreme expansion of the 10 cutters is thus provided, insuring a complete reaming action, or the complete reaming away of the annular shoulder or obstruction beneath the casing. This is of 15 high importance in underreaming work, and the invention provides for obtaining such highly important spread or expansion 20 within the small range of play possible or feasible to be accommodated in a tool of the relatively compact or small form or dimensions permitted by the conditions under 25 which its operation and use take place. Likewise, such extreme expansion is permitted in accordance with the invention without diminishing the strength and stress-resistance of the working parts, or inviting 30 breakage or failure thereof.

When it is desired to withdraw the reamer from working position, after reaming the desired extent of formation to permit further lowering of the casing, the 35 underreamer body A is drawn upwardly by the string-carrying cable carrying with it the cutters until the riding bearings 20^a engage with the shoe or lower end of the casing, whereupon the cutters are temporarily held against vertical movement 40 while the body continues to rise, the relative movement so produced causing the bearings 20^b to ride downwardly and inwardly upon the upper spreading bearings 9^a , and subsequently the shoulders 20^a to ride downwardly and inwardly upon the lower spreading 45 bearings 9^b . This downward and inward collapsing movement is initiated immediately, avoiding any pinch as between the cutters and the lugs, due to the slight 50 downward inclination of the upper spreading bearings 9^a . With the parts brought to the positions shown in Fig. 2, upward urge being given the underreamer through the cable, the cutters and the correspondingly lowered spring-actuated rod will follow the body upwardly permitting the reamer to be withdrawn from the upper end of the casing.

One further particular advantage attaching 60 to the pivotal suspension of the cutters at opposite sides of the longitudinal axis of the underreamer, consists in the resultant disposition of the cutters each approximately in a vertical plane when in collapsed 65 position. Owing to such disposition the cut-

ters operate to greater advantage than would be the case if the cutters were suspended at a single pivotal point. It therefore results that the cutters much more readily pass down through the casing when collapsed in 70 introducing the reamer into the hole; the tendency of the cutters, due to their frictional engagement with the casing to pinch and bind and jam outwardly against the casing, being almost entirely overcome. 75 Thus this provision for positioning the cutters lengthwise at opposite sides of the center of the reamer and approximately parallel to the longitudinal axis of the reamer, results in unobstructed lowering of the reamer 80 through the casing. One great difficulty attending the use of underreamers has always been this tendency of the cutters to stick and jam in the casing. This tendency has at times rendered it necessary to tie the cutters 85 together before introducing them through the casing. No such tying or other precautionary measure is necessary with the reamer of the present invention.

It is manifest that many variations, 90 changes and modifications, all with relation to the foregoing description and statement and the showing of the drawing, may be made, in practicing the invention and adapting it to varying conditions of use and service, without departing from the spirit of 95 the invention and a fair interpretation thereof.

Having thus disclosed our invention, we claim and desire to secure by Letters Patent: 100
 1. In an underreamer, a body and a pair of cutters, the body and cutters having interengaging means for causing expansion of the cutters, cutter supporting and actuating means including a spring actuated 105 plunger having a lower centrally aligned flat head with opposite parallel faces, the cutters having each a flat laterally offset shank, which shanks fit flatly one against one face and the other against the opposite 110 parallel face of the flat head, and pivoted connections for the cutters to the head embodying two pivots, one for one cutter at one face of the head and the other for the other cutter at the opposite face of the head, 115 said pivots being parallel to each other and at right angles to the head faces and spaced apart on opposite sides of a central longitudinal plane perpendicular to the head faces.

2. In an underreamer, a body and a pair of cutters, the body and cutters having interengaging means for causing expansion of the cutters, the cutters being swingingly movable in a plane of movement longitudinal and central of the body, said cutters having flat shanks which overlap each other and lie at opposite sides of the central longitudinal plane of movement of the cutters, and cutter supporting and actuating means which 120 125 130

include two pivots upon one of which one cutter shank is mounted and on the other of which the other cutter shank is mounted, said pivots being parallel to each other and parallel to and spaced apart on opposite sides of, a central longitudinal plane which is perpendicular to the longitudinal plane of movement of the cutters.

In testimony whereof we have signed our names to this specification in the presence of 10 two subscribing witnesses.
